DISTRESS SIGNAL FOR ELECTRICALLY-OPERATED CLOCKS

William P. Elliot, New York, N. Y.

Application December 28, 1934, Serial No. 759,504

5 Claims. (Cl. 58—26)

Among the principal objects which the present invention has in view are: To provide clocks of the character mentioned with illuminated index for disclosing the fact of what is styled "periods of distress", namely, periods during which the clock operation has been interrupted through failure of electric current supply; to employ as a signal to indicate interruption periods an illuminated electrically-operated gas glow lamp of low wattage consumption; to control the current employed in the illumination referred to; and to simplify the construction.

Drawing

15 Figure 1 is a view of a typical electrically-operated clock used here for illustration purposes only, and equipped with a distress signal mechanism, constructed and arranged in accordance with the present invention, the rear of the 20 clock casing being removed.

Figure 2 is a plan view of the works, or construction of the said typical clock and of the distress detector and signal mechanism constructed and arranged in accordance with the 25 present invention.

Figure 3 is a detailed view in perspective showing the switch for operating the distress signal, said switch being constructed and arranged in accordance with the present invention.

30 Figure 4 is a diagrammatic view showing the electrical wiring and parts affected thereby as employed for operating the distress signal as indicated.

Description

35 As seen in the drawing, a clock of the type mentioned, and to which the present invention is applied, has an electric motor provided with a field winding 5, and field core 6 for operating the rotor 7, operatively connected with the clock 40 mechanism.

The magnetic pull of the field core 6 when energized is utilized in the present invention to hold in vigilant position the switch member 8.

45 The member 8 is pivotally mounted on a shaft 9. The switch member 8 and insulated member 10 are off center or so disposed that when not held by the magnetic pull of the motor field, in the raised position shown in Figure 1, the former 50 will fall between the switch members 11 to complete the electrical circuit employing wires 12, 13 and 16. The position of the switch member 8 incident to and following any period of distress or failure of operation of the clock due to lack 55 of current supply is shown in Figure 3.

To prevent switch members 8 and 10 from reclining backward when being swung into an elevated position, a stop arm 20 has been so placed as to rebound these switch members to a tilted position towards members 11, with a slight gap 5 between the members 8 and 20 after member 8 has come to a fixed upright position.

In the present invention this switch remains constant until manually reset, or until the shaft 9 is manually turned to reset the switch member 10 10 8 and insulated member 10 to the upright position shown in Figure 1 of the drawing, and the soft iron magnetic detent 14 is in proximity to the field core 6 of the motor to be held by magnetic attraction of the motor field core when energized, in position to maintain the elevated position of the switch member 8. The magnetic pull is sufficient to hold the detent 14 in the upright 15 service position of member 8.

When, for any reason, the electric current 20 operating the motive power of the clock is interrupted, the field core 6 will become de-magnetized. In this condition the detent 14 ceases to hold the switch member 8 in elevated position and the weight of the members 8 and 10 causes 25 the member 8 to be dropped between the switch members 11 to the position shown best in Figure 3 of the drawing.

When, now, the motive current is re-established, the clock mechanism is again put in operation with the result that unless otherwise notified, the person depending upon the clock for time would conclude that it was registering correctly. This would be misleading as to the time, due to the loss during the period when the mechanism 30 was in distress. It is to effect a positive indication of such distress, or of distressed periods that I have provided a neon gas glow lamp 15 so disposed as to be visible when illuminated. The current causing the lamp 15 to glow is supplied 35 by the wiring 12, 13 and 16, which are connected with the electrodes within the lamp 15. The quantity flow of the current supplied to the lamp 15 is regulated by a resistance 18, placed in series 40 in the circuit wiring 12, 13 and 16. The wires 13 and 16, as is shown by the diagram in Figure 4 of the drawing, are cut in and securely connected with the wires of the operating circuit of the 45 clock motor.

When gas glow lamps of ratings less than $\frac{1}{4}$ 50 of a watt are used, there is apt to be, at times, a slight flickering glow in such lamps with the switch member 8 in an upright open position especially when the lamp wire 13 is being serviced from the grounded wire of the house circuit. To 55

eliminate this annoying feature, there is provided a resistor 17 shunted by wire 19 across the lamp wires 12 and 16.

It will be observed that when now the current is supplied to the clock motor subsequent to a distressed period, the switch member 8 is in contact with the members 11 thus establishing a circuit through the lamp 15, and so causing the same to glow, with the result that the interested persons are made aware of, or notified, that the time record as shown by the clock is not to be relied upon.

By using an illuminated member such as the lamp 15, a simple and reliable indicating signal is provided, and one which can be readily recognized or seen in a lighted room as well as when the room is darkened.

When now the time indicating members such as the hands of the clock have been readjusted to correct positions, the shaft 9 is turned manually by revolving resetting knob 9' to lift the switch member 8 from contact with the members 11 to be held in this elevated position thereafter by the magnetic attraction of the motor field core 6 for the magnetic detent 14.

It will be understood that while I have herein described the use of the neon gas glow lamp, I do not wish to be restricted to such employment, as I have used the neon type of light only because, in my opinion, the low wattage required to illuminate the lamp, its low heat radiation and its highly conspicuous light together with other features has made it the most desirable element of the character mentioned.

35 I claim:

1. In combination with a clock actuated by an electric motor, a distress signal comprising an electrically operated gas glow lamp, a circuit for operating the same cut in upon the operating circuit of the clock motor, and means for limiting and controlling the electrical current to operate the said gas glow lamp subsequent to a distress period of the motive power of the clock, said means embodying a resistance element shunted across said lamp and a resistance element disposed in series, both in the circuit servicing said lamp.

2. In combination with a clock actuated by an electric motor, a distress signal comprising an electrically operated gas glow lamp, a circuit for operating the same cut in upon the operating circuit of the clock motor, and means for limiting and controlling the electrical current to operate the said gas glow lamp subsequent to a distress period of the motive power of the clock, said means embodying a resistance element shunted across said lamp and a resistance element disposed in series, both in the circuit servicing said lamp, and means operating mechanically for closing the circuit for operating said lamp, said circuit being completed immediately following the suspension of the motive power of the clock works.

3. In combination with a clock actuated by an electric motor, a distress signal comprising an electrically operated gas glow lamp, a circuit for operating the same cut in upon the operating circuit of the clock motor, and means for limit-

ing and controlling the electrical current to operate the said gas glow lamp subsequent to a distress period of the motive power of the clock, said means embodying a resistance element shunted across said lamp and a resistance element disposed in series, both in the circuit servicing said lamp, and means operating mechanically for closing the circuit for operating said lamp, said circuit being completed immediately following the suspension of the motive power of the clock, said last named means embodying rigid switch terminals and a weighted switch member, said switch member being adapted to drop between and electrically bridge the switch terminals when not held therefrom by the magnetic attraction of the magnetic field of said motor when electrically energized.

4. In combination with a clock actuated by an electric motor, a distress signal comprising an electrically operated gas glow lamp, a circuit for operating the same cut in upon the operating circuit of the clock motor, and means for limiting and controlling the electrical current to operate the said gas glow lamp subsequent to a distress period of the motive power of the clock, said means embodying a resistance element shunted across said lamp and a resistance element disposed in series, both in the circuit servicing said lamp, and means operating mechanically for closing the circuit for operating said lamp, said circuit being completed immediately following the suspension of the motive power of the clock works, said last named means embodying rigid switch terminals and a weighted switch member, said switch member being adapted to drop between and electrically bridge the switch terminals when not held therefrom by the magnetic attraction of the magnetic field of said motor when electrically energized, and manual means for returning the switch member to its open circuit position.

5. In combination with a clock actuated by an electric motor, a distress signal comprising an electrically operated gas glow lamp, a circuit for operating the same cut in upon the operating circuit of the clock motor, and means for limiting and controlling the electrical current to operate the said gas glow lamp subsequent to a distress period of the motive power of the clock, said means embodying a resistance element shunted across said lamp and a resistance element disposed in series, both in the circuit servicing said lamp, and means including an armature, a member magnetically energized by the same electric current as that servicing the clock motor, and a switch controlled thereby for closing the circuit for operating said lamp; said switch being normally held in an open circuit position by the magnetic action on said armature, said means being arranged to move automatically to a closed circuit position with the armature outside of the effective range of the magnetic attraction of said member, on failure of the electric current servicing the clock motor, and manual means for re-establishing the open circuit position of said switch member.
